CLAIM

The ornamental design for a rub rail for a vehicle, as shown and described.

DESCRIPTION

FIG. 1 is a perspective view of a rub rail for a vehicle showing my new design;

FIG. 2 is a front view thereof;

FIG. 3 is a rear view thereof;

FIG. 4 is a top view thereof, the bottom view being substantially identical;

FIG. 5 is an end view thereof, the opposing end view being substantially identical; and,

FIG. 6 is a cross sectional view thereof, taken along line 6—6 in FIG. 2.
